J. A. SUMNER.
CLEANING AND WAXING PAD FOR SAD IRONS.
APPLICATION FILED OCT. 31, 1912.

Patented Sept. 30, 1913.

UNITED STATES PATENT OFFICE.

JAMES A. SUMNER, OF SHENANDOAH, IOWA.

CLEANING AND WAXING PAD FOR SAD-IRONS.

1,074,478.

Specification of Letters Patent. Patented Sept. 30, 1913.

Application filed October 31, 1912. Serial No. 728,961.

To all whom it may concern:

Be it known that I, JAMES A. SUMNER, a citizen of the United States, residing at Shenandoah, in the county of Page and State of Iowa, have invented certain new and useful Improvements in Cleaning and Waxing Pads for Sad-Irons; and I do declare the following to be a full, clear, and exact description of the invention, such as will enable others skilled in the art to which it appertains to make and use the same.

This invention relates to improvements in cleaning and waxing pads for sad irons.

One object of the invention is to provide a pad of this character having an improved construction and arrangement of wax holding and applying sheet and means for removably fastening the same to the block or body of the pad whereby the sheet may be readily renewed when necessary.

Another object is to provide a cleaning and waxing pad having on one side an abrasive surface upon which the iron may be cleaned and polished prior to being waxed by the waxing sheet on the reverse side of the pad.

With these and other objects in view, the invention consists of certain novel features, and the construction and arrangement of parts as will be more fully described and claimed.

In the accompanying drawings; Figure 1 is a perspective view of my improved pad; Fig. 2 is a similar view of the same in a position reverse to that shown in Fig. 1; Fig. 3 is a vertical longitudinal section of the pad; Fig. 4 is a vertical cross section thereof; and Fig. 5 is an end view with parts broken out and with the parts in position to permit the wax holding sheet to be removed from the block.

My improved waxing pad comprises a block 1 which may be formed of any suitable material and is preferably constructed of wood. The block 1 may also be of any size and shape but is here shown and is preferably of flat rectangular form. In one face of the block is formed a series of parallel longitudinally disposed grooves 2 which are preferably curved or gradually increase in depth from their ends to the center thereof as clearly shown in Fig. 3 of the drawings. The grooves 2 are filled with wax or a waxing composition which may be renewed when necessary as will be hereinafter described. In one of the side

edges of the block is formed a longitudinal groove or slit 3 the purpose of which will be hereinafter described.

The reverse face of the block from that having the wax containing grooves 2 is provided with an abrasive surface which is preferably formed by a sheet of emery paper or cloth 4 glued or otherwise firmly secured to the block. Adapted to be engaged with the grooved face of the block is a waxing sheet 5 formed of any suitable material such as paper, cloth or a combination of paper and cloth and which is saturated with wax or a waxing composition. The sheet 5 is of sufficient size to cover one face of the block and to extend downwardly over the side edges thereof. One of the downwardly extending side edges of the sheet 5 is inserted in the groove or slit 3 in one edge of the block while the opposite side edge of the sheet is folded down over the opposite side of the block and firmly secured by a combined clamping member and iron scraper 6. The clamping member and scraper 6 is in the form of a bail shaped plate or bar corresponding in length to the length of the block 1 and having its right angular ends engaging the ends of the block and pivotally secured thereto at one end by a pivot screw 7 and at the opposite end by a screw eye 8, said screw eye being provided to form a convenient means for hanging the device on a nail or other support when not in use.

By pivotally connecting the clamping member and scraper to the block in the manner described, it will be seen that when said member is swung downwardly over the side edge of the block with which the free edge of the sheet 5 is engaged that the sheet will be drawn tightly across the side of the block and the edge of the sheet firmly clamped into engagement with the edge of the block. In order to limit the downward movement of the bail 6 when swung to an operative position, I provide stop pins 9 which are arranged at suitable positions in the ends of the block as shown. On one edge of the side portion of the bail shaped clamping and scraper member 6 is a right angularly bent outwardly projecting flange 10 which serves as a scraper by means of which any accumulations may be removed from the face of the iron. The flange 10 also serves as a handle for conveniently operating the member 6 and also as a reinforcement or brace for the long side of the clamping member.

By constructing my improved waxing and cleaning device as herein shown and described, it will be seen that the waxing sheet 5 when worn out may be readily removed 5 and replaced by a new sheet and that when the waxing composition has been used from the grooves 2 in the block that said grooves may be again filled thus permitting the continued use of the device. The abrasive sheet 10 on the reverse side of the block may also be removed when worn out and a new abrasive sheet secured in position on this side of the block.

From the foregoing description taken in 15 connection with the accompanying drawings, the construction and operation of the invention will be readily understood without requiring a more extended explanation.

Various changes in the form, proportion 20 and the minor details of construction may be resorted to without departing from the principle or sacrificing any of the advantages of this invention as defined and claimed.

Having thus described my invention, what I claim is:

1. A waxing and cleaning pad for sad irons comprising a block having in one side a series of wax receiving grooves and in 30 one edge a longitudinal slit, a waxing composition arranged in said grooves, an abrasive surface on the opposite side of the block from that having said grooves, a waxing sheet arranged over the side of the block 35 having said grooves, said sheet having one edge engaged with the longitudinal slit in the edge of the block, and a combined iron scraper and clamp pivotally connected to

the block and adapted to grip and firmly clamp the free end of the sheet to the opposite edge of the block from that to which the opposite end of the sheet is secured. 40

2. A cleaning and waxing pad for sad irons comprising a block having in one edge a slit, a waxing sheet arranged over one 45 side of said block and having one edge inserted in said slit, a combined clamping member and iron scraper comprising a bail shaped bar having its ends pivotally connected to the ends of the block and adapted 50 to be swung down into engagement with the opposite side edge of the block from that having said slit, whereby the free end of said waxing sheet is clamped to the adjacent edge of the block, and an outwardly 55 projecting flange on one edge of said clamping member.

3. A cleaning and waxing pad of the character described comprising a block having a wax holding depression in one face 60 thereof, and an abrasive surface on another face, said block having a slit in one side thereof, a waxing sheet arranged over the face of the block having the wax holding depression therein, said sheet having one 65 edge engaged with the longitudinal slit in the block, and a waxing sheet clamp engaged with the block and adapted to clamp the free edge of said sheet thereto.

In testimony whereof I have hereunto set 70 my hand in presence of two subscribing witnesses.

JAMES A. SUMNER.
